UNITED STATES PATENT OFFICE.

ERSKINE RAMSAY, OF BIRMINGHAM, ALABAMA.

LONG-WALL MINING SHIELD.

Application filed November 8, 1926, Serial No. 147,043. Renewed February 18, 1928.

This invention has general reference to shields which are adapted for use in trenching, tunneling, stoping, sumping, and other excavating or mining operations; and relates 5 more particularly to such shields which are especially suitable for employment in long-wall mining, as in the mining of coal along an extended face of the vein.

A primary object of the present invention 10 is to produce a portable shield which is adapted to protect miners and others engaged in excavating work or the like, against injury from falling or cave-in material, and to eliminate, or at least minimize, the shoring, cribbing, or other timbering that has heretofore been required for such work.

A further object is to produce such a shield which is adapted for use in connection with long-wall mining or other excavating work 20 along an extended working face, and which is sufficiently flexible to allow for variations in the surfaces with which it contacts.

A further object is to produce such a shield which is equipped with mechanical 25 means for moving it.

And a still further object is so to design and arrange the parts of such a shield that the pressure of the loose material behind it will tend to retain it in the desired position 30 relative to the face that is being worked, and to facilitate its advance toward said face when the shield is moved.

The means by which the foregoing and other objects are accomplished by my invention, and the manner of their accomplishment, readily will be understood from the following description on reference to the accompanying drawings, which depict preferred embodiments of the invention, and in 40 which:—

Fig. 1 is a sectional top plan view of a portion of my improved shield and the conveying machinery associated therewith.

Fig. 2 is a rear elevation of the parts 45 shown in Fig. 1.

Fig. 3 is a transverse section showing the shield and associated mechanism on a larger scale, and indicating the normal position of the shield relative to the loose material behind it and to the working face.

Fig. 4 is a front elevation of the portion 50 of the shield shown in Fig. 3.

Fig. 5 is a fragmentary detail view of a modified form of buffer plate to be used at 55 the rear side of the shield.

Fig. 6 is a view similar to Fig. 3, showing

a modified form of the shield in which the advancing mechanism is of the caterpillar tractor type.

Fig. 7 is a diagrammatic view, showing a 60 preferred manner of arranging mine tunnels for the use of the shield. For the purpose of illustrating a typical form of the invention, I have shown in the drawings, and shall describe hereinafter, a mining 65 shield in the construction of which structural steel shapes and plates are employed, but it is manifest that other members, such as castings or forgings or different forms of steel members, may be substituted if desired, 70 without in any way departing from the intended scope of the invention. Also, in referring hereinafter, and in the appended claims, to certain parts as being "secured together", it is to be understood that said 75 expression is intended to apply broadly either to unitary construction or to the joining together of parts in any suitable manner, as, for example, by bolting, riveting, or welding.

As shown in the drawings, in which like parts are identified by corresponding reference characters throughout the several views, the shield preferably comprises a series of 80 triangular frames, each made up of a pair 85 of structural channels 7, placed back to back, with their lower ends secured to a steel base-plate 8 near the rear edge thereof, the two channels of each pair being spaced a sufficient distance apart to permit a buffer plate 9 90 to be secured therebetween with its rear edge extending considerably beyond the channels, and said channels being preferably forwardly inclined relative to the base-plate 8; and a pair of channels 10, placed back to 95 back, with their lower ends secured to said base-plate near the forward edge thereof, said channels being disposed substantially at right angles to the top of the base plate, and their flanges being cut away to permit a 100 pair of structural angles 11 to have their lower ends secured to the outer faces of the channels 10 at the upper ends thereof, the other ends of said angles being secured to a channel 12 which extends longitudinally of 105 the base-plate 8, and to which the upper ends of the forwardly-inclined channels 7 are secured, as by means of angle clips 13. A filler plate 14 is secured between the upper ends of the angles 11 to space said ends the 110 same distance apart that the lower ends of said angles are separated due to the presence

of the webs of the channels 10 therebetween. The various frames of the shield are secured together at the top by structural angles 15, which are secured to the angles 11, as by the 5 angle clips 16, and a structural channel 17 is secured to the angles 15 and to the channels 12. The lower ends of the channels 10 of the various frames are secured together and to the base-plate 8 by channels 18 and 19, 10 and the lower ends of the channels 7 are similarly secured together and to said base-plate by channels 20 and 21. Between the buffer-plates 9 of the various frames, and secured to the flanges of the channels 7, are 15 special ship-channel members 22, arranged parallel with the base-plate, and three ship-channels 23, 24 and 25 are likewise secured to said flanges, adjacent channel 22, with their flanges secured together, the channels 23 and 20 25 being secured to the buffer plates 9, as by angle clips 26.

A floor-plate 27 is secured to the channels 18, 19, 20 and 21, and serves as a working platform in the tunnel-like structure on 25 which the miners may stand. A structural angle 28 has one of its legs secured to the outer face of the web of each of the channels 7, and the other leg of said angle forms with the rearmost flange of said channel a groove 30 for the loose reception of timbers 29, or other equivalent members, such as metal plates, which prevent the loose material at the rear of the shield from falling upon the working-platform 27, while at the same time 35 said members are movable upward to afford access by the miners to said loose material. Between the angles 11 of the various frames there are loosely supported pipes or rods such as may be required to protect the interior of the shield from falling coal, and to 40 one thereof is detachably connected a wire rope or other suitable suspension member 31 for supporting a pneumatic pick or drill 32, which is connected by a hose 33 with a compressed air pipe 34. A hydraulic ram 35 is 45 pivotally supported by a bracket 36 from the channel 21, the plunger of said ram terminating at its free end in a wedge-shaped portion 37 extending beyond the rear edge of the base-plate 8, and said ram being suitably connected with water pipes 38 and 39. As best shown in Fig. 1, the rear edge of 50 the base-plate 8 is cut away between the frames of the shield, so as to facilitate bringing the ends 37 of the plungers of the rams 35 into engagement with the surface on which said base-plate rests. A spray pipe 40 is supported by the angles 10, in position to direct small streams of water downwardly 55 against the working-face 41.

The channels 18 and 19 serve as guides for the flights 42 of horizontally-arranged flight-conveyors 43 and 44, which deliver to a conveyor 45, the details of which are not shown 60 in the drawings, but which preferably is

adapted to elevate the material received from conveyors 43 and 44, sufficiently to deliver it into mine-cars or other means of transportation located in the tunnel 46. The three conveyors are driven by motors 47 and 70 48 through suitable gearing and other power-transmission units. As clearly shown in Fig. 3, the front edge of the base-plate 8 preferably is provided with a replaceable toe-strip 49, and said edge extends beyond 75 the outer ends of the flights of the flight-conveyor at that side of the base plate, so that said flights ordinarily do not come in contact with the working-face 41, but bits, such as indicated at 42^a in Fig. 3, may be 80 secured to the outer ends of some or all of the flights, to provide for the cutting away of any projections from the lower extremity of the working-face, such as might interfere 85 with the advancement of the shield.

In the modified form of buffer-plate 50, shown in Fig. 5, the exposed rear edge of said plate is provided with a series of similar teeth 51, which are so shaped as to be adapted to cause fracture and partial disintegration of 90 any pieces of shale or other frangible material which may fall or be pressed against said teeth, and which if not broken up might cause excessive pressure of the shield 95 against the working-face.

The inclination of the angles 11 is substantially the same as that which is normally assumed by the working-face 41 as the material composing it is power-picked or hand-picked down, shot down, or broken by 100 subsidence pressure, and the lower end of each of said angles terminates at such a height, and is so shaped, as to afford working clearance for the picks or drills 32. In fact the shield is so designed as to permit 105 of the miners having access to any part of the face of coal being worked.

The modified form of shield shown in Fig. 6 is provided with tractors of the caterpillar type instead of the rams 35, for advancing the shield toward the working-face. Said tractors may be of any preferred form, and the one shown in Fig. 6 is illustrated conventionally as comprising the usual endless chain 52 and end sprockets 53 and 54, no 110 shoes being shown, since the particular character thereof that may be employed forms no part of the present invention. The base-plate 8 has a transverse opening adapted to permit the lower one of the tractor chain to 115 travel therein, with its shoes engaging the surface on which the base-plate rests, and throughout the length of the shield, lining-plates 55 and 56 are secured to the upper surface of the base-plate in position to provide 120 surfaces over which the two runs of each of the flight conveyors 43 and 44 travel. The position of the compressed air pipe 34, from which air is supplied for the operation 125 of the picks or drills 32, is such that it is 130

cleared by the chains and shoes of the tractors; the sprocket 53 is located in the space between the lower ends of the channels 20 and 21, with its shaft 57 supported between adjacent ones of the channels 7; and the sprocket 54 is located in the space between the lower ends of the channels 18 and 19, with its shaft 58 supported between adjacent ones of the channels 10. The head shafts 58 of the tractors may be driven from individual motors (not shown), or a plurality of them may be driven from a single motor. From the foregoing description, the operation and utility of the invention readily will be apparent. The picks or drills 32 are spaced such a distance or distances apart as will conform with the length of the portion of the working-face that is intended to be worked by one drill-operator, and the rams, or the tractors used instead thereof, preferably are similarly spaced, so that each may be operated by one of the drill-runners, and so that they may co-operate in moving the shield uniformly. The rear side of the shield is sufficiently closed by the channels 22, 23, 24, 25 and 20 and the timbers 29 to protect the miners, all of said members being strongly reinforced by the channels 7 and the buffer plates 9 or 50; the top of the shield is closed by the channel 17, reinforced by the channels 12 and the angles 15; and at the front of the shield are the angles 11, the channels 10, and the deflecting bars or pipes 30. It is preferred that at suitable distances apart there shall be breaks in all of the longitudinal members of the shield, so that it may be sufficiently flexible to allow for inequalities in the surface upon which it rests, and irregularities in the working-face. As the working face is sumped or under-cut or picked down with the picks or drills 32, or otherwise worked with power tools or by hand, or settles by subsidence pressure, the material that is loosened, and that which constitutes the upper portion of the working-face, and which is dislodged by the working of the lower portion of said face, falls upon the forward runs of the flight conveyors 43 and 44, by which it is delivered to the conveyor 45, and by it discharged into mine-cars or other means of transportation located in the tunnel 46. When the working-face has thus been cut away throughout its length to the depth to which the picks or drills 32 are adapted to work efficiently, the shield is advanced toward the working-face 41 by means of the hydraulic-rams or pushers 35, or by the tractors, assisted by the pressure of the loose material behind the shield, until the toe-strip 49 of the base-plate 8 takes against or is close to the extreme lower portion of the working-face, all of said rams or said tractors preferably being operated simultaneously and uniformly, so as not to impose excessive distortional strains

upon the shield, although the width and thickness of the metal base-plate 8, and the manner in which it is reinforced by the other members, are such as to adapt it to withstand great lateral stresses, while being sufficiently flexible to allow for inequalities in the surfaces engaged by it. As the working-face is cut away, and the shield is advanced, the material which dislodges or breaks away from the roof falls behind the shield, any of such material which strikes the top of the shield being deflected rearwardly by the inclined longitudinal channel 17, and the larger pieces being broken up by the buffer-plates 9 or 50. Said loose material will press against the inclined rear side of the shield, and thus tend to hold it in its advanced position, and to facilitate its advancement by the rams or the tractors, if not actually to advance it. Should it be desired to secure access to the material at the rear side of the shield, either to loosen it or break it up with the picks or drills, or for any other purpose, such as to dispose of waste or refuse material, the timbers 29 may be moved upward in the grooves in which their ends are placed, thereby leaving an opening between the channel 20 and channel 25. When it is desired to change the position of any one of the picks or drills 32, it is only necessary to detach its supporting pendant 31 from that one of the pipes or rods 30 from which it is suspended, and to change the point of support of said pendant, the length of the hose 33 connecting the pick or drill with the compressed air pipe 34 preferably being such as to permit of moving the pick or drill to any part of the space in which it is intended to be operated, without having to change the point of connection to the air pipe. It will be apparent that by the use of my improved shield in the manner just described, the workmen standing upon the working-platform 27 are fully protected against injury by material either dislodged from the working face or falling from the roof, and a protected passageway is provided throughout the length of the working-face and into the tunnel 46, yet no timbering is required at any point, except in said tunnel, which serves as a means of exit from the mine or other excavation, and provides for the transportation of excavated material therefrom. As indicated in Fig. 7, a preferred arrangement of tunnels in a mine in which my improved shield is to be used, comprises parallel tunnels A and B extending transversely of the vein at the respective ends of the length of vein to be worked, and parallel connecting tunnels, such as indicated by C, D and E, at right angles to the transverse tunnels A and B, the distance between each two adjacent connecting tunnels being substantially equal to the length of the min-

- ing shield. Thus, when the delivery conveyor 45 is placed in that one of the connecting tunnels at which it is desired to start the work, as in tunnel D, the ends of 5 the shield will extend substantially half way to the adjacent connecting tunnels C and E, and when the delivery conveyor 45 is moved to either one of said adjacent tunnels, as to tunnel E, and the shield is moved correspondingly, one end of the shield will extend 10 to the line along which its other end was advanced during its preceding run. The shield is advanced from tunnel A toward tunnel B, and when it has reached the latter 15 tunnel it is disassembled, either only sufficiently to permit it to be reversed so as to work back toward tunnel A, or to such an extent as to permit of its being transported back to tunnel A and reassembled therein in 20 position to work again toward tunnel B. The connections of the longitudinal members to the triangular frames preferably are bolted, to facilitate knocking down, transporting and reassembling the parts of the shield. 25 Various modifications of minor details of the improvements disclosed herein doubtless readily will suggest themselves to those skilled in this art, but such modifications fall within the scope of my inventive rights, and 30 my invention is not to be construed as being limited to any details not specifically set out in the claims.
- Having thus fully disclosed the invention, what I claim as new, and seek to secure by 35 Letters Patent, is:—
1. A portable shield adapted for use in long-wall mining and other similar excavating operations, said shield having a front face and a rear face, with a working space 40 therebetween, and means forming part of said faces, closing the upper portions thereof against access of material to the interior of the shield, while the front face is open sufficiently to give access to the work.
  - 45 2. A shield conforming to claim 1, said shield being of very much greater length than width, and the working space being substantially continuous throughout the length of the shield.
  - 50 3. A shield conforming to claim 1, and having its front face rearwardly inclined.
  4. A shield conforming to claim 1, and having its rear face forwardly inclined.
  - 55 5. A shield conforming to claim 1, and being of substantially triangular transverse cross-sectional configuration.
  6. A shield conforming to claim 1, and having its two faces inclined toward each other, and secured together at the top and 60 at the bottom.
  7. A shield conforming to claim 1, and having a base-plate secured between its two faces at the bottom of the shield substantially throughout its length.
  - 65 8. A shield conforming to claim 1, and

having a base-plate secured between its two faces at the bottom of the shield, and a working-platform above said base-plate, said platform extending substantially throughout the length of the shield.

9. A shield conforming to claim 1, having its two faces converging toward the top of the shield, and an inclined deflector extending longitudinally of the shield at its top.

10. The combination, with a portable 75 shield adapted for use in long-wall mining and other similar excavating operations, said shield comprising a front face and a rear face, having a working space therebetween, and said faces being partially closed against 80 access of material to the interior of the shield, and secured together at top and bottom, of means carried by said shield for imparting movement to the shield.

11. The combination of elements recited in 85 claim 10, in which the moving means is effective upon the shield at the base thereof.

12. The combination of elements recited in claim 10, in which the moving means is adapted to act against a surface that is adjacent the shield.

13. The combination of elements recited in claim 10, in which the moving means is adapted to act against the surface on which the base of the shield rests.

14. The combination of elements recited in claim 10, in which the moving means comprises a plurality of power units placed at different points longitudinally of the shield substantially throughout its length.

15. The combination, with a shield adapted for use in long-wall mining and other similar excavating operations, said shield comprising a front face and a rear face, having a working space therebetween, said faces 100 being partially closed against access of material to the interior of the shield, of a plurality of power-driven excavating tools supported within the shield and placed at different points longitudinally thereof.

16. The combination of elements recited in claim 15, each of the excavating tools being controllable from within the working space, and being effective outside the shield.

17. The combination with a portable 115 shield adapted for use in long-wall mining and other similar excavating operations, said shield comprising a front face and a rear face, having a working space therebetween, and said faces being partially closed against 120 access of material to the interior of the shield, of a conveyor located within the shield and adapted to transport material longitudinally thereof.

18. The combination of elements recited in claim 17, in which the conveyor extends substantially throughout the length of the shield.

19. A portable shield adapted for use in 125 long-wall mining and other similar exca-

vating operations, said shield comprising a series of spaced, substantially triangular frames, connected at three sides by members extending longitudinally of the shield.

5 20. A shield conforming to claim 19, two sides of the shield being closed against access of material to the interior thereof.

21. A shield conforming to claim 19, two sides of the shield being closed against access 10 of material to the interior thereof, and a third side being partially so closed.

22. A shield conforming to claim 19, two sides of the shield being closed against access of material to the interior thereof, and only 15 the upper portion of the third side being so closed.

23. A portable shield adapted for use in mining and other excavation of an extended surface, said shield comprising a tunnel-like 20 structure partially open on its front side and being of very much greater length than

width, said structure being sufficiently flexible to allow for inequalities in its supporting surface.

24. A portable shield adapted for use in 25 an untimbered portion of a mine or other excavation, said shield having two oppositely-inclined sides, one of which is partially open and is opposed to the face to be worked upon, while the other one of said 30 sides is closed, and is reinforced to withstand the pressure of material dislodged from the roof during the excavating operation.

25. A shield conforming to claim 24, in 35 which the inclination of the closed side of the shield is such that the pressure of the dislodged material thereagainst tends to advance the shield toward the work-face.

In testimony whereof I affix my signature.

ERSKINE RAMSAY.
